FRICTION IGNITION

Jesse Randolph Swan, Jr., Pasadena, Calif.

Application September 3, 1937, Serial No. 162,381

2 Claims. (Cl. 131—7)

This invention relates to a new and useful attachment which serves as a lighting means of a so-called self-lighting cigarette and the like, and is an improvement on prior inventions and 5 has for its principal objects to provide a simple and sufficient means whereby the cigarette may be readily ignited without the use of a match or any other independent lighting device.

The principal object of the invention is to provide a ready lighting attachment, simple in design, economical and efficient that will obviate the necessity of a smoker having to carry about his person matches or any other independent lighting apparatus for the use of lighting a cigarette.

The primary object of the invention is to provide for instantaneous ignition by inflammable and igniting material combined in the manner herein illustrated and applied to what is commonly known as a cigarette, which with the proper use, will cause instantaneous ignition and function as a light for a cigarette, or other similar article where instantaneous ignition is of benefit.

A further object is to produce instantaneous ignition by taking hold of the free end of the string, the other end being congealed in the amalgam of matter, a quick jerky movement of the free end of the string in the intended direction breaking the amalgam of matter or the igniter tip thus to cause instantaneous ignition.

The combustible compound of matter that is to be used and so designated as the igniter tip, is similar in formula and substance as that compound of matter contained in the head of an ordinary match, varying somewhat in quantity and combustible qualities.

With these and other objects in view, the invention resides in certain novel constructions, 40 combinations and arrangement of parts, the essential features of which are hereinafter more fully described and particularly pointed out in the appended claims, and are illustrated in the accompanying drawing forming a part of this specification, in which;

Figure 1 is a perspective view of a portion of a cigarette having my improved igniting unit attached thereto.

Figure 2 is a plan view of the unit, particularly showing the mount prior to its affixation to the sides of the cigarette.

Figure 3 is a side elevation of a portion of the cigarette showing the lighter unit in place.

Figure 4 is a side elevation of a portion of the

cigarette, illustrating another aspect of the lighter unit.

Figure 5 is a perspective view illustrating the mode of use of the invention.

Referring now to the drawing by characters 5 of reference. Figure 1 is a cigarette of conventional shape and is shown as having one of my complete improved lighting devices applied to the one end thereof. The cigarette is referred to by character "A" and comprises the usual 10 outer wrapper that covers and holds the tobacco of an ordinary cigarette.

The lighting attachment constituting the present invention comprises a rectangular mount 1 formed of paper or any other suitable material, 15 sufficiently narrow in width so that on each side thereof where crossing over the end of the cigarette and down along the opposite sides thereof, it will leave a portion of the end of the cigarette or the tobacco contained therein exposed to facilitate a draft and expose the tobacco to the oxygen of the air. And that the ends of the paper crossing over the end of the cigarette and down the side thereof to be sufficient in length to fasten to a portion of the sides of the cigarette, 20 approximately one half inch, and by adhesion affixed to the one end and sides of the cigarette. And to be of sufficient tensile strength that will withstand the effect of the force necessarily created by the quick jerky movement of the string 25 2 that is congealed in an ignitable element 3 so that when the necessary force is applied to break element 3 that part 1 will stay intact congealed to the cigarette and likewise to burn when the cigarette is being consumed by fire.

The numeral 2 indicates a string constructed of asbestos or any non-inflammable material as a safety protection so when severed from element 3 it has served its desired purpose and may be discarded without fear of continued or renewed 40 ignition. The string may be designated as a trigger. It is to have sufficient tensile strength that when applied with a quick jerky movement it will not break; but the action will break element 3. String 2 is to be in size, length, design 45 and color, suitable for the intended purpose, one end of the string to be incorporated and congealed in element 3 with the other end of the string being free and loose, approximately one and one-half inches in length, long enough however so as to enable it to be grasped with the fingers.

The numeral 3 is an element similar in formula and substance as that contained in an ordinary common match, and to be of sufficient 55

quantity and contain sufficient combustible quality of matter, as when the breaking of same takes place by the quick jerky movement of the trigger ignition will result. Element 3 is to be only a drop in size just to cover the end of the paper 1 where it passes over the end of the cigarette, and is to be spotted by adhesion to part 4. The string 2 is to be incorporated in the amalgam mass 3 and is to become a part and parcel of the element 3 during the stage and process of congealing, so that when the molten mass or element 3 is set or hardened, the string 2 will be embodied therein, and that when the string 2 is jerked in the intended direction it will break the element 3 and cause ignition.

While I have described what I deem to be the most desirable embodiment of my invention, it is obvious that many of the details may be varied without in any way departing from the spirit of my invention; and I desire to be understood that I may make changes in the construction and in the combination and arrangement of the several parts, provided that such changes fall within the scope of the appended claims.

I am aware that prior to my invention every substance used to cause friction ignition, every substance used in the manufacture of paper, every substance used in the manufacture of string, have all been in public use. From the construction shown by the drawing it is obvious to any one skilled in the art that frequent lack of uniformity in the size and shape of cigarettes will not prevent its ignition because all parts necessary to ignite are self embodied and congealed

in the amalgam of matter and compose one unit and will ignite perfectly by a quick jerky movement of the string, or trigger, in the intended direction.

This lighting feature permits the entire lighter to be manufactured as a separate unit and it can be supplied to cigarette manufacturers completely embodied and congealed as one unit and ready to apply to the end of a cigarette.

Having thus described my invention what I claim and desire to secure by Letters Patent is:

1. A lighter for a cigarette and similar tobacco roll consisting of an ignitable element, a rectangular paper mount of narrow strip form to which said element is affixed, said mount being superimposed over one end of the cigarette and attached to the sides thereof and being narrower than the diameter of the roll to expose a draft space beside at least one edge of the mount, and a string embedded at one end in said element being adapted to frictionally ignite the element by pulling and then thrown away, said string being non-inflammable to insure avoidance of its burning.

2. A lighter for a cigarette of the type having a paper mount applied over one end of the cigarette and having an ignitable element affixed to said mount in line with said end, a string embedded in said ignitable element and extending off loosely therefrom, said string being pulled to frictionally ignite the element and being composed of non-inflammable material.
